UNITED STATES PATENT OFFICE.

LOUIS FABER, OF WASHINGTON, DISTRICT OF COLUMBIA.

REFRIGERATOR FOR PRESERVING OYSTERS, CLAMS, &c.

SPECIFICATION forming part of Letters Patent No. 310,886, dated January 20, 1885.

Application filed November 15, 1884. (No model.)

To all whom it may concern:

Be it known that I, LOUIS FABER, a citizen of the United States, residing at Washington, in the District of Columbia, have invented a 5 new and useful Improvement in Refrigerators for Preserving Oysters and Clams, of which the following is a specification, reference being had to the accompanying drawings.

This invention relates to refrigerators for 10 oysters, clams, and the like, and is specially designed for use in restaurants, eating-saloons, and dining-rooms, where it is desirable to have oysters in the shell kept constantly on hand for immediate use.

15 The object of the invention is to provide a simple, inexpensive, and ornamental stand or case, of any desirable size, either to rest on the bar, when only a small supply is desired to be preserved, or on the floor, similar to an ordinary 20 refrigerator, in such places where a constant demand is made for oysters served on the "half-shell" or raw, said case or stand being in convenient reach of the person behind the bar or counter, so that the oysters or clams may be 25 removed, shucked, and served to the customers without loss of time.

With these and other objects in view the 30 said invention consists in certain details of construction and combination of parts, as hereinafter set forth, and particularly pointed out in the claims.

In the accompanying drawings, Figure 1 is 35 a perspective view of my improved oyster-refrigerator, the door of the outer box or casing being open to allow the removal of the contents of the inner receptacle. Fig. 2 is a longitudinal sectional view of the same. Fig. 3 is a horizontal sectional view on the line $x-x$, Fig. 2. Fig. 4 is a detached view, in perspective, 40 of one of the corners of the inner case, illustrating the manner of securing the supports of the detachable bottom upon which the ice rests.

Like letters are used to indicate corresponding 45 parts in the several figures of the drawings.

Referring to the drawings, A designates the outer box or casing, rectangular in form, and having a suitable base or supported on legs,

as found convenient and desirable. The box 50 or casing is preferably constructed of wood, with glass panels at the sides, the bottom being lined with zinc, copper, or other non-corrodible metal, and the top being provided with an opening, which is closed by a detachable cover, B.

C designates the inner removable receptacle for the oysters or clams, preferably constructed of round wire interlaced or twined around suitable corner posts or rods, the wires running diagonally in opposite directions, and soldered together and to the corner rods, to make a permanent fixture. The bottom and four sides are formed in this manner, but one of the sides—the front—is cut out or left open, 65 as at D. A door, E, is provided in the front wall of the outer casing or box, which door is of about the same size as the opening D, so that when it is thrown open, as in Fig. 1, access to the oysters contained in the receptacle 70 C is readily permitted through the aforesaid opening. It will be observed that the opening in the top of the outer casing or box is sufficiently large to permit the removal of the inner receptacle, C, through the same when it 75 is desired to clean the parts of the refrigerator, or when packing or storing the oysters within the receptacle.

F designates the detachable false bottom on which the ice rests, which bottom is constructed 80 in a similar manner to the receptacle C—that is, having corner rods connected by diagonally-arranged cross-wires secured together by solder in the manner well known. This bottom F is supported on four wire braces or supports, 85 G, (see Fig. 4,) which extend across the receptacle at the corners, the ends of the wire supports being twisted, turned, or coiled around the diagonally-arranged wires at the point where they meet or cross each other, as will be clearly seen. In this manner there can be no possibility of the detachment of the wire braces or supports, and the latter cannot work down out of place. These wire braces or supports should be attached at a suitable distance from 90 the top of the receptacle, which is left open at that point to allow for the reception of a piece of ice of sufficient size, the latter being 95

supported solely by the detachable false bottom.

The receptacle C rests on the lined bottom of the box A a suitable distance from the sides thereof, so as not to mar, soil, or break the glass panels. The spaces between the cross-wires of the detachable bottom F and the receptacle C allows the passage of the water as the ice melts, the water descending to the bottom, which is provided with an outlet opening, a, having a tube or pipe, H, communicating therewith for carrying off the waste water to any desired point.

The operation of my invention will be readily understood from the foregoing description, taken in connection with the annexed drawings. When it is desired to renew the supply of oysters to the receptacle C, the latter is withdrawn through the opening in the top of the box or casing A, as it is far more convenient to pack the oysters within the receptacle when it is out of the box than if retained therein. After the removal of the receptacle the oysters or clams, whichever may be desired to use, are packed or stored one upon the other in the manner well known until the wire braces or supports G are reached. It is not necessary to take any particular pains in the storing of the articles, for the oysters being irregular in form, they may be merely laid loosely together and yet will not fall down or become displaced, as they will mutually cling to and support each other. It will also be observed that since the oysters cannot be packed without leaving a short space between the same, this space will permit the free passage of the water melted from the ice. When this packing has been effected, the receptacle is replaced within the outer casing or box, A, and the detachable bottom F laid upon the wire braces or supports G above the oysters. A piece of ice of sufficient size is then placed upon the bottom F, and the cover B applied to close the box and prevent the ingress of warm air, after which the refrigerator is in condition for use. It will be observed that when the ice melts the water trickles through the bottom F down through the oysters, and upon the bottom of the box A, where it is carried off, as before stated. This passage of the water through the oysters keeps the latter in good condition, so that there is no possibility of spoiling. In refrigerators where the ice is merely used to cool the air surrounding the oysters and the water is carried off, the oysters spoil or become worthless in a very short time; but by passing the water through them they are kept alive and in the best possible condition for eating, since they are preserved within their native element.

In large refrigerators, where it would require considerable labor to load the receptacle and return it to the box A', I prefer to pack the oysters with the said receptacle retained in its position; also, when constructing large-sized refrigerators it would not be desirable

to have glass panels in the sides of the outer casing or box, as that would involve considerable expense and would soon become broken; but in small-sized stands, which are usually placed on the eating-bars of restaurants, it would add to the appearance of the refrigerator to use the glass panels and make it as ornamental in construction as the taste and fancy of the owner may dictate.

The door E should be kept closed except when it is desired to remove some of the oysters to supply the demands of a customer. This is effected as will be seen by reference to Fig. 1, the oysters being in convenient reach for removal, and since the sides of the receptacle C support the oysters when any are withdrawn, the balance or remainder will not be precipitated down, as would be the case were no support provided.

The device is simple in construction, inexpensive to manufacture, and will prove of great utility for the purposes intended. It will fill a long-felt want in restaurants, where it will not only fulfill its natural functions, but will also serve as an article of decoration.

Having described my invention, I claim—

1. In a refrigerator for oysters, &c., the combination, with the outer box or casing, of the inner receptacle for the oysters, a removable bottom provided in the upper end of the latter, and the ice resting on the bottom, the water melting from the ice trickling through the bottom and oysters down to the bottom of the box, where it is carried off, as and for the purpose set forth.

2. In a refrigerator for oysters, the combination, with the outer box or casing, of the inner receptacle for the oysters, and a false bottom provided in the upper end of the latter a suitable distance from the top to receive a supply of ice, as set forth.

3. In a refrigerator for oysters, the combination, with the outer casing or box, of the inner receptacle for the oysters, having an opening formed in one side, the ice supported at the upper end of the receptacle, and a door provided in the outer box or casing on a line with the opening in the receptacle, as and for the purpose set forth.

4. In a refrigerator for oysters, &c., the combination, with the outer casing or box, of the inner receptacle for the oysters, constructed of wire interlaced, twined, or otherwise secured together, and having means for supporting the ice at the upper end thereof, as set forth.

5. In a refrigerator for oysters, &c., the combination, with the outer casing or box, of the inner receptacle for the oysters, constructed of an open frame-work or provided with openings in a solid frame-work, and a bottom supported at the upper end of the receptacle and similarly constructed, as and for the purposes set forth.

6. In a refrigerator for oysters, &c., the combination, with the outer casing or box hav-

ing an opening at its upper end closed by a cover, of the inner receptacle disposed within the box or casing, and a bottom supported at the upper end of the receptacle, as set forth.

5 7. In a refrigerator for oysters, &c., the combination, with the outer box or casing provided with a door, of the inner receptacle arranged within the box or casing, a false bottom supported at the upper end of the said receptacle, an opening in one side of the latter, and a pipe communicating with the bottom of the box for carrying off the waste water, as set forth.

15 8. In a refrigerator, the combination, with the outer casing or box, of the inner receptacle, wire braces or supports attached to the sides of the latter at the corners, and a false bottom resting on the braces or supports, as set forth.

20 9. In a refrigerator, the combination, with

the outer box or casing, of the inner receptacle for containing the oysters, constructed of an open frame-work, as and for the purpose set forth.

10 10. In a refrigerator, the combination, with 25 the outer casing or box, of the perforated false bottom supported within the box or casing, and receiving the ice, the oysters being placed in the space below the false bottom, and the water melting from the ice trickling through 30 the oysters to the bottom of the casing, where it may be drawn off, as set forth.

In testimony that I claim the foregoing as my own I have hereto affixed my signature in presence of two witnesses.

LOUIS FABER.
